UNITED STATES PATENT OFFICE.

FRANK L. VERGES, OF FREMONT, OHIO, ASSIGNOR OF ONE-TENTH TO HARRY ZIMMERMAN, OF FREMONT, OHIO.

MULTIPLY BUFFER.

Application filed October 15, 1923. Serial No. 688,587.

This invention relates to fabric rubbing devices.

This invention has utility when incorporated in multiply fabric buffers especially for buffing metallic surfaces, even in connection with abrasives.

Referring to the drawings:—

Fig. 1 is a side elevation with parts broken away of an embodiment of the invention as a multiply duck or canvas fabric buffering disc;

Fig. 2 is a fragmentary view on a reduced scale of a mounting for operating the discs with Fig. 1;

Fig. 3 is a fragmentary view of a buffering disc of the type shown in Fig. 1, but designed as a stiffer type of construction;

Fig. 4 is a fragmentary view of a buffering disc wherein the stitching is extended, but there is still provided a uniform endless series of pockets although the pockets are of somewhat different shape than the pockets of Fig. 1 and Fig. 3;

Fig. 5 is a fragmentary view of a fabric buffering disc wherein the stitching is tangential;

Fig. 6 is a side elevation with parts broken away of an embodiment of the invention similar to Fig. 1, but with the primary assembling spiral stitching extending into the field of the radial stitching;

Fig. 7 is a fragmentary edge view with parts broken away of an assembling of the buffer sections as buffer stiffened by glue for harder or coarser work as in roughing or finishing wheel, and

Fig. 8 is a view in side elevation parts being broken away of uniform crisscross stitching as supplemented by a spiral stitching in a buffer disc section.

Plies 1 of fabric may be of canvas, cotton duck or other woven stock having warp and woof at 90° from each other, the successive plies 1 being shifted 45°, approximately such angle to give dissimilar direction to the threads in the adjacent plies and thereby render the plies less subject to similar fraying. These plies may be of different weight stock and as assembled into discs 2 may be in quantities of, say, from 15 to 20 plies each. There may in practice be variations over or under this number of plies to meet varying conditions of operation. In use buffers may be subjected to arduous service, even as to considerable grinding action un-

der which circumstances more coarse abrasives are employed. Abrasives may be of emery, tripoli, lime, rouge, and other grinding or polishing materials or compounds.

These buffering discs have greater efficiency at higher speeds of operation. However, the frictional action tends to build up temperature, and to neutralize such a condition, there is incorporated in the discs 2 of this disclosure as may be found desirable, ply 3. This ply 3 may in an assembly of, say, 16 plies, 1 to be placed between the 8th and 9th plies, and concentric therewith. The impregnation of this ply 3 may be varied to suit operating conditions. A desirable lubricant for the buffer may be obtained by impregnating the ply 3 with a compound of tallow, beeswax and paraffine wax. This may be in equal proportions by weight or other variation even to an excess paraffine to twice the quantity of the tallow and beeswax. Such compound is used as a liquid by warming and the disc 3 impregnated by dipping thereinto.

The discs 1, 3, may be assembled, say by central spiral anchoring stitching 4, to provide a hub region approximating washers 5 in diameter. The discs have central openings 6, allowing the discs to be moved along the shaft 7 against washer 8 of similar size to washer 5, and the grouping of discs 2 fixed with the shaft 7 by running nut 9 up on such shaft. This shaft 7 is rotated by belt 10 about pulley 11. The shaft 7 is shown as carried by bearings 12 mounted on machine frame 13.

The real working portion of the buffer is that region beyond the stitching 4. With no stitching, at high speeds there is a tendency due to centrifugal force to have the disc hold to a straight outward plane. The greater the speed, the more rigid this holding, due to centrifugal force. In practice with the holding of an article against the disc to be treated by the discs, say by incorporating with the rotating discs the polishing material, the holding up action is hardly sufficient. The discs are accordingly reinforced by stitching 14, providing therebetween pockets 15. There is accordingly herein an annular series of similar pockets which are uniform and tend to hold the polishing material. This reenforcing due to the radial stitching 14 is of less strength as to stiffening the discs at the outer region

of the disc 2. However, as the discs are rotated at high speed, the centrifugal force supplements this stitching 14, and a sufficiently rigid construction is provided. In practice the discs fray out in operation and provide a loose face which may have the frayed out stitches extend back, say $3/8$ " and the fraying material following thereupon. As the use of the buffer continues, its diameter is decreased as the stock wears away. This decreasing diameter of the buffer with a maintained speed for the shaft 7 means that there is a gradually decreased linear speed for the working face of the buffer edges. Accordingly the centrifugal action for stiffening the buffing face is decreasing in the disclosure herein. Actually there is not a decrease in the stiffness of this buffer for the reason that the stitching 14 is greater per unit of extent of the buffing surface at the less radial distance. These pockets 15, which, while decreasing in capacity, are still uniformly distributed and more numerous per unit of area of the buffer. The efficiency of this buffer is maintained throughout its life and its life is one for wearing down of its stock in a complete use of the buffing portion thereof.

Buffing disc 16 has stitches 17 radial but more closely assembled than the stitches 14 of the disc 2, and accordingly pockets 18 between the stitchings 17 are smaller. The increased stitching per unit of area of the buffing disc 16 means this disc may be operated at lower speeds, or be subjected to harder usage at similar speeds than the disc 2. In practice these speeds of operation while in many cases running from 2,000 to 2,500 R. P. M. have also been used even up to 3,000 to 3,500 R. P. M. Disc 19 is shown as having arc stitching 20 therein for longer stitch travel than the direct radial stitches 14, 17. However, here there is still an endless annular series of similar pockets 21. Disc 22 instead of having curved stitching 20 is shown as having tangential stitching 23 providing similar pockets 24.

Disc section 25 is herein shown as having radial stitching 26 intersected by constant pitch spiral stitching 27 to form shallow pockets 28 as radially open. This spiral stitching contributes uniformly to the stability or approximately uniformly to increasing the stiffness of the disc section. The relatively shallow pockets 28 tend to hold the abrasive against travel inward and thereby the abrasive as applied to the wheel is more economically delivered in disc operation.

In instances where even additional rigidity is desired in section assembly, the disc sections 25 may have the face plies 29 thereof dipped in glue, and as so impregnated plies 29 of the sections 25 may be assembled into a relatively hard wheel 30 which may

carry even a coarse emery as the abrasive and stand up well thereunder for heavy roughing operations in metal finishing.

Buffing disc section 31 is shown as having increasing pitch spiral stitching 32 for less stiffening effect on the outer or high lineal speed portion, and closer stitching on the inner or less lineal speed portion. This stitching spiral is accordingly diverging. This disc 31 as so variably stitched by the spiral 32 may have strengthening stitching by supplemental stitches 33 or even by further stitching 34. These stitchings produce pockets 35 which are in peripheral series and shallow.

The buffers as herein disclosed may not only be self lubricated by incorporating the impregnated plies 3 therewith, but automatically compensate for maintained stiffness under varying radial speed conditions as the buffer wears down, but also have the polishing material holding pockets uniform throughout the fray in each working diameter of the buffer. Remnants 36 may be used in piecing out the plies and in no way detract therefrom, while such is a factor of economy in production.

In the building up of glued buffing wheels hereunder a buffing section may have a ply on one side thereof given a heavy coat of glue, a buffing section placed thereover with the upper ply of said second section given a heavy coat of glue as a liquid and this operation continued to the thickness of buffing wheel desired. The lower discs may be laid upon a paper and a paper placed on the top of the upper disc. The assembled sections may then be subjected to pressure and such pressure maintained for not only effecting impregnation of the buffing sections by forcing the glue through the needle holes along the lines of stitching as spiral and intersecting as well as radial, but as to any excess of such glue exuding such from the wheel.

After the pressure is released further seasoning by exposure to the air gives the wheel further stability. It is then ready to be centered for its arbor and then peripherally dressed down and glue coated for carrying the abrasive. These wheels by their stitching not only provide substantial stiffening due to the intersecting glue lines therethrough but are substantial against fraying and wearing so that as an abrasive face has worn therefrom a redressing may occur and a supplemental glue and abrasive tread applied to be repeated throughout the life of the wheel. A further factor due to this character of seaming is that there is practically no tendency whatever for the edges of this disc to roll as a glued disc.

As a buffing disc without glue there is minimum tendency of the edges to roll. Furthermore there is no necessity whatso-

ever to rake this disc in order to provide a buffing face. Again in practice with the stitching extending outward, the threads of the stitching wear down with the wheel face.

5 As to the intersecting stitching the threads are knotted or tied with each other by the crossovers so that there can in no instance herein be any unraveling of the stitching threads which might be freed, and as

10 thrown from the disc, have a tendency to wrap the work and pull such from the operator, with danger to the operator, as well as the destruction of the article. This means that these wheels are effective for uniform

15 operation with a minimum of danger incident thereto.

What is claimed and it is desired to secure by Letters Patent is:—

1. A buffing disc section embodying a plurality of concentric flat plies of fabric adjacently dissimilarly extending as to the fabric threads, a general assembling spiral stitching therefor, and additionally a pocket forming stitching overlapping said spiral stitching. 20

2. A buffing disc section embodying concentric fabric flat plies, stitching substantially concentric with the periphery of the wheel and intersecting stitching through said plies overlapping said arc stitching. 30

In witness whereof I affix my signature.
FRANK L. YERGES.
